UNITED STATES PATENT OFFICE

ENOCH G. KETTELKAMP, OF KANSAS CITY, MISSOURI

ADJUSTABLE SPLINT

Application filed May 26, 1928. Serial No. 280,799.

My invention relates to adjustable splints and one object is to provide a simple appliance of this character of minimum weight and which can be folded into compact form for transportation as regular equipment of the physician, so that it may be at hand for the emergencies that often arise and for which the physician is not usually equipped to give the best attention.

10 A further object is to provide an appliance of this character which can be used both in regular and emergency treatments of fractures of the upper and lower extremities. As an emergency appliance the device can be used for any fracture of the arm by holding the latter in fixed position so that danger of additional truma to the injured part during transportation will be reduced to a minimum.

15 20 Another object is to provide an appliance which can be readily adjusted to either arm and whereby traction may be applied in such manner as to overcome muscle contraction which has a tendency to cause overriding of the fragments.

25 Other objects will hereinafter appear and in order that the invention may be fully understood reference will now be had to the accompanying drawings, in which:

30 Fig. 1 shows the device adjusted to the upper portion of the body for holding the arm in an extended and approximately horizontal position.

Fig. 2 shows the device applied to the 35 lower portion of the body for holding one of the legs in extended position.

Fig. 3 shows the device applied to the upper portion of the body and adjusted for holding the arm away from the body and with the forearm arranged approximately 40 at rightangles to the upper arm.

Fig. 4 is a detail perspective view of the device detached from the body and adjusted in full and dotted lines for holding either 45 the right or left arm in different positions.

Fig. 5 is a view somewhat similar to Fig. 2 with the device detached from the body.

Fig. 6 shows the device folded into compact form for storage or transportation.

50 In carrying out the invention I employ a

body plate 2 which is curved to approximately fit the curvature of the different portions of the body to which it is to be applied. The plate 2 is made of thin material so that it may be flexed to better fit the 55 different portions of the body and is provided with straps 4, 6 and 8 and buckles 10, 12 and 14 whereby it may be firmly drawn against and held in position upon the body. The straps 4, 6 and 8 are attached to one side 60 of the plate 2 while the buckles 10, 12 and 14 are secured to respective short straps 16, 18 and 20 at the opposite side of the plate 2.

22 designates a bar upon which the body plate 2 is fixedly mounted. Said bar 22 is connected at one end by a hinge 23 to a brace member 24 and at its opposite end by a hinge 25 to a second bar 26, which latter is provided with a fixedly mounted second plate 28 and a second brace member 27. The 70 brace member 27 is secured to the bar 26 by a hinge 29 and adjustably and detachably connected to the brace member 24 by a bolt 31 equipped with a nut 33.

30 designates a third bar which is fixed to a third plate 32 and adjustably and detachably connected at one end to the second bar 26 by suitable means such as a bolt 34 and a wing nut 36, and detachably connected at its opposite end to a fourth bar 38 by 80 bolts 40 and 42 and nuts 44 and 46. The bar 38 is bent approximately at rightangles and provided at one end with a traction member 48 consisting in the present instance of a screw eye equipped with nuts 50 and 52 85 which are arranged at opposite sides of said bar 38.

54 designates a third brace member which may be connected to the bars 26 and 28 to reinforce the latter as disclosed by Fig. 1, 80 which shows said brace member detachably secured in place by suitable means such as the bolt 34 and bolts 56 and 58. The bolts 56 and 58 are equipped with nuts 60 and 62, respectively.

95 In the treatment of a fracture requiring the arm of the patient to be held in an extended position as shown by Fig. 1, the plate 2 is placed against the side of the body with the hinged end 25 of the bars 22 100

and 26 disposed in the axilla. The plate 2 is secured to the body with the straps 4, 6 and 8, and the plates 28 and 32 are held in alinement to support the arm by the bars 26 and 30, and the brace members 24, 27 and 54. Traction may be applied to the arm of the patient for overcoming contraction of the muscles, which has a tendency to cause the adjacent ends of the fragments to over-ride each other, by running a piece of adhesive tape A through a cord B and applying the ends of said tape to the arm. The cord B is then secured to the eye of the traction member 48 and drawn taut by proper adjustment of the nut 52, after which the arm may be bandaged to the appliance. Should it be found desirable to raise or lower the arm from the position shown by Fig. 1 it can be readily accomplished by sliding the brace member 27 upwardly or downwardly upon the brace member 24 to the desired point and then securing said brace members firmly together with the bolt 31 which may be placed through any of the holes 66 and 68 in the brace members 24 and 27, respectively.

If the fracture is such as to render it desirable to flex the arm at the elbow as shown by Fig. 3, for overcoming anterior or posterior bowing of the arm, the brace member 54 is removed and the bar 30 is swung on the bolt 34 at a suitable angle to the bar 26 and the plate 28. The bar 30 is then secured from further movement by the brace member 54, one end of which is secured to the intermediate portions of the bar 26 and the plate 28 with the bolt 60, while its opposite end is secured to the intermediate portions of the bar 30 and the plate 32 with the bolt 58. The bar 30 and the plate 32 have a series of registering holes 59 through any of which the bolt 58 can be placed when it is desired to change the angle of the plate 32 with respect to the plate 28. If the fracture is such as to require traction on the upper arm the bar 38 is transferred from the front end of the bar 30 to the rear end thereof and the forward end of bar 26, and secured in place with the bolts 34 and 56. Adhesive tape A is then applied to the upper arm and connected to the traction member 48 with the cord B, after which the arm may be bandaged to the appliance.

In emergency treatment of a fracture of any part of the leg or thigh the splint is extended full length in order to reach from the top of the iliac crest to a point beneath the foot as shown by Fig. 2. The plate 2 is firmly secured to the body by means of the straps 4, 6 and 8 and the leg is held in extended position by means of the adhesive tape A, the cord B and the traction member 48. The leg can then be bandaged its entire length to the splint so that the patient can be safely transported to a hospital or other

point where the usual treatment for such cases can be administered.

Fig. 4 discloses how the plate 32 may be swung on the bolt 34 to different positions with respect to the plate 28, thereby rendering the splint applicable to either the right or left arm. The splint is preferably made of aluminum so that X-ray pictures can be taken of a fracture without removing the splint and also for the purpose of reducing the weight of the splint to a minimum, so that it may be readily carried as a part of the regular equipment of a physician. When not in use the appliance can be folded into compact form as disclosed by Fig. 6.

From the foregoing description it is apparent that I have provided an appliance which is well adapted for the purpose intended and while I have shown one form of the appliance I reserve all rights to such other forms and modifications as properly fall within the spirit and scope of the invention as claimed.

Having thus described my invention, what I claim and desire to secure by Letters Patent, is:

1. In an appliance of the character described, a body plate, a brace member hinged at one end to the lower end of said body plate and provided near its free end with a plurality of holes, a second plate hinged at one end to the upper end of the body plate, a second brace member hinged at one end to said second plate and provided at its free end with a plurality of holes spaced to register with the holes in the first brace member when the free ends of said brace members are arranged in an overlapping position to hold the plates at an angle to each other, an element adapted to be placed in any two of the registering holes for securing the overlapping ends of the brace members together, a third plate operably connected to the free end of said second plate, a bar bent at an angle and adapted to be secured to either the free end of said third plate or at the connection of the latter with the second plate, and a traction member threaded in said bar.

2. In an appliance of the character described, a body plate, a second plate hinged at one end to the upper end of the body plate, a third plate operably connected to the free end of said second plate, a bar bent at an angle and adapted to be secured to either the free end of said third plate or at the connection of the latter with the second plate, and a traction member threaded in said bar.

In testimony whereof I affix my signature.

ENOCH G. KETTELKAMP. 125
